UNITED STATES PATENT OFFICE.

ERNEST GIGLIO, OF UNION CITY, NEW JERSEY.

DESIGN FOR AN EYEGLASS FRAME.

Application filed January 11, 1927. Serial No. 20,333. Term of patent 14 years.

To all whom it may concern:

Be it known that I, ERNEST GIGLIO, a citizen of the United States, residing at Union City, county of Hudson, and State of New Jersey, have invented a new, original, and ornamental Design for Eyeglass Frames, of which the following is a specification, reference being had to the accompanying drawing, forming part thereof.

In said drawing, Figure 1 is a perspective and Figure 2 is a front face elevation of the eyeglass frames, showing my new design.

I claim:

The ornamental design for an eyeglass frame, as shown.

Dated this 10th day of January, 1927.

ERNEST GIGLIO.
